W. H. ROSE,
LIQUID SOAP DISPENSER,
APPLICATION FILED OCT. 19, 1920.

1,392,600.

Patented Oct. 4, 1921.

UNITED STATES PATENT OFFICE.

WILLIAM H. ROSE, OF JERSEY CITY, NEW JERSEY.

LIQUID-SOAP DISPENSER.

1,392,600.

Specification of Letters Patent.

Patented Oct. 4, 1921.

Application filed October 19, 1920. Serial No. 417,965.

To all whom it may concern:

Be it known that I, WILLIAM H. ROSE, a citizen of the United States, and residing at Jersey City, Hudson county, State of New Jersey, have invented certain new and useful Improvements in Liquid-Soap Dispensers, of which the following is a specification.

The present invention relates to fluid dispensers, particularly to devices for dispensing liquid soap, such as are commonly used in hotels, office buildings, public wash rooms and often in private dwellings.

These dispensers usually comprise a container or receptacle for holding a considerable quantity of soap in liquid form, and a manually operable pumping device by means of which small measured quantities of liquid soap are withdrawn from the container and discharged into the outstretched hand of the operator. A common defect of dispensers of this class heretofore designed or suggested is that an objectionable leakage of the soap often occurs, this leakage being due in part to the nature of the soap itself which will escape through minute openings and cracks which are not large enough to allow the escape of water. When such leakage is detected it is, of course, necessary to replace the defective parts or the parts which do not fit together properly, and where pistons, springs, and other metallic parts are utilized such replacement may be difficult and may involve a considerable expense, as compared with the entire cost of the dispenser. Leakage of soap in this manner renders the device unsightly.

It is an object of the present invention to provide a liquid soap dispenser having a pumping device which is positive in its ejecting action; which will not easily break down in use; and in which the component parts are of the simplest design, enabling it to be made at a minimum cost thereby cutting the expense of original installation and reducing the cost of maintenance. The pumping device is so designed and constructed also that leakage of the soap from the container is practically eliminated, rendering it necessary to replace the parts only when they are worn out through long continued use. The invention may be embodied in a number of different forms and several modifications thereof will be described in

this specification and illustrated in the accompanying drawings, in which,

Figure 1 is a side elevation of a dispenser and its supporting bracket, parts of the dispenser and bracket being broken away to show the pumping mechanism;

Fig. 2 is a section on line 2-2 of Fig. 1;

Fig. 3 is a view similar to Fig. 1 omitting to show portions of the receptacle and bracket and illustrating a modified form of the pumping device;

Fig. 4 is a similar view but showing a third modification of the pumping device;

Figs. 5 and 6 are top views of the valves illustrated in Figs. 3 and 4 respectively;

Fig. 7 is a bottom view of the soft rubber member illustrated in Figs. 3 and 4;

Fig. 8 is a top view of a modified form of cup-shaped rubber member adapted to be used in place of that illustrated in Fig. 1.

Referring particularly to Fig. 1, a supporting bracket is indicated at 10 and a glass or metal receptacle or container at 11, this container having an externally threaded tubular neck portion 12 at its bottom which screws into the correspondingly threaded upper end of a passageway 13 which extends vertically through the outer end of the bracket. Immediately below the lower end of neck 12 the passage 13 is provided with an upwardly facing annular shoulder 14 and clamped between the neck 12 and this annular shoulder are two soft rubber members 15 and 16. The lower member 15 is disk-shaped with a central aperture 15' which opens into a contractile rubber tube 15" extending vertically downward, the wall thickness of this tube being greater on one side than on the other, for a purpose hereinafter to be fully explained.

The upper member 16 has an annular peripheral portion and cup or dome-shaped central portion having a central aperture and one or more inlet ports 17. A spindle 18 of wood, hard rubber, or other like material extends downwardly through the container, through the central apertures in the rubber members 15 and 16, and through the contractile tube 15". A block or disk 19, which may be of cork or other material is secured to this spindle immediately above the member 16, this spindle having the handle or knob 20 at its upper end by means of which it may be conveniently grasped and

vertically reciprocated. The upward movement of the spindle is limited by a restraining member 21 which may have different forms, but is preferably a cord or tape the ends of which are clamped between the neck 12 of the container and the disk member 16 the intermediate portion passing over block 19, and being wrapped around the spindle so that it will not be displaced.

10 In Fig. 1 the parts are illustrated in the position which they normally occupy. When it is desired to eject soap from the container, the operator holds one hand beneath the aperture in the bracket and presses 15 on the knob 20 with the other. The block 19 immediately depresses the top of the dome-shaped rubber member beneath it and, when this has been partially flattened, serves as a valve, closing the ports 17. Further downward movement of the block creates pressure within the pump chamber, the walls of which are formed by the two rubber members, and the soap therein is forced out between the wall of the contractile tube 25 15" and the spindle 18, the tube 15 immediately contracting after the pressure is relieved, preventing any flow of fluid due to gravity alone. When the knob or handle is released, the member 16 springs back to its 30 former shape and returns the spindle to its initial position and the ports 17 are again uncovered by the block to permit the entrance of soap into the pump chamber. Upon the return movement of the spindle 35 and before ports 17 are uncovered by disk 19, a suction may be created in the chamber which would tend to draw tube 15" upwardly and into the chamber, but this tube is formed as has been before explained, with 40 one side considerably thicker than the other, the thick side being stiff enough to successively resist the force of the suction within the chamber while the thin side permits the tube to radially expand to allow the 45 escape of fluid when the handle is reciprocated.

Instead of the cup-shaped rubber member 16 having a series of perforations in its top, a rubber member 16' may be used if desired 50 which has an elongated slot 17' in its top. This member operates exactly as does the member 16, the slot 17' taking the place of the small openings 17 of that member.

In the modification illustrated in Fig. 3, 55 the disk member 15^a is of hard rubber or fiber, and the cup shaped soft rubber member 16^a extends downwardly and fits closely within a similarly shaped shell or casing 30 which forms part of the bracket 10^a. A 60 non-return valve 19^a controls the flow through an inlet port in the disk, this valve having a short stem 18^a attached thereto which extends through the outlet tube at the bottom of the rubber member 16^a. Pressure is applied to the flexible wall of the

pump chamber by means of a horizontal manually operable plunger 31 and the liquid is ejected between the stem 18^a and the inner surface of the contractile rubber tube.

A third modification is illustrated in Fig. 4. Here the disk 15^b and the cup-shaped rubber member 16^b are positioned as in the modification illustrated in Fig. 3 and the non-return valve 19^b also has a stem 18^b integral therewith, which stem extends 75 through the contractile outlet tube. Pressure is applied, however, by means of a vertically moved tubular member 32 which is adapted to be moved upwardly by the hand of the operator until it contacts with and 80 deflects the wall of member 16^b, causing thereby the immediate closure of the non-return valve and the creation of pressure in the pump chamber which, as before, results in the ejection of fluid between the spindle 85 and the inner wall of the contractile outlet tube.

Other modifications may be devised and it will be obvious to those skilled in the art that the invention is not limited in scope 90 to those embodiments described and illustrated.

Having thus described the invention what is claimed as new and desired to be secured by Letters Patent is:

1. The combination with a fluid soap tank of a discharge device comprising a flexible pump chamber having an inlet provided with a non-return valve and a self-closing outlet, a stem connected to said non-return 100 valve and extending through said outlet, and means for applying pressure to the wall of the pump chamber to eject fluid from said outlet.

2. The combination with a fluid soap tank 105 and a support therefor of a discharge device comprising a horizontally arranged disk and a cup-shaped flexible member which, together with the disk, incloses a pump chamber, the edges of the disk and 110 flexible member being clamped between the tank and support, said pump chamber having an inlet provided with a non-return valve, and a self-closing outlet, and a horizontally movable plunger adapted to be 115 manually operated to apply pressure to the cup-shaped flexible member to eject the fluid from said outlet.

3. The combination with a fluid soap tank having a circular discharge orifice and a support therefor of a discharge device comprising a horizontally arranged disk and a cup-shaped flexible member below the disk which, together with the disk, incloses a pump chamber, the edges of the disk and 125 flexible member being clamped between the edge of the discharge orifice and support, said disk having an inlet aperture controlled by a non-return valve, and said cup-shaped member having a self-closing outlet at its 130

lowest point, and a horizontally movable plunger for applying pressure to the cup-shaped member to eject fluid through said outlet.

- 5 4. The combination with a fluid soap tank of a discharge device comprising a horizontally arranged disk having an inlet aperture controlled by a non-return valve, a cup-shaped flexible member below the disk having a self-closing outlet aperture at its lowest point in vertical alinement with the inlet aperture, said disk and member inclosing a pump chamber, a spindle secured to said valve and extending through said outlet aperture, and means for applying pressure to said flexible member to eject fluid from said outlet.
- 10 5. The combination with a fluid soap tank of a discharge device comprising a pump chamber with a flexible portion of soft rubber, said chamber having an inlet provided with a non-return valve and having an outlet aperture opening into a contractile tube, a spindle extending through said tube and fitting closely the inner surface thereof, and means for applying pressure to the flexible
- 20
- 25

wall of the pump chamber to thereby expand said tube and eject fluid between the tube and spindle.

6. The combination with a fluid soap tank of a discharge device comprising a pump chamber with a portion of soft rubber, said chamber having an inlet provided with a non-return valve and having an outlet aperture opening into a contractile rubber tube one side of which is thicker and stiffer than the other, a spindle secured to the non-return valve and extending through the tube and closely fitting the inner surface thereof, and means for applying pressure to the flexible wall of the pump chamber to thereby stretch said tube and eject fluid between the tube and spindle.

7. The combination with a fluid soap tank of a discharge device including a pump chamber having a flexible wall and a self closing outlet and a rigid and non-compressible member extending through said outlet and against which the edges of the outlet opening bear.

In testimony whereof I affix my signature.

WILLIAM H. ROSE.
